UNITED STATES PATENT OFFICE.

EDWARD R. TISCHER, OF HOUSTON, TEXAS, ASSIGNOR OF FORTY-FIVE PER CENT. TO
GUS EMMERT, OF HOUSTON, TEXAS.

GIN.

1,227,845.

Specification of Letters Patent. Patented Jan. 13, 1920.

Application filed May 5, 1919. Serial No. 294,303.

To all whom it may concern:

Be it known that I, EDWARD R. TISCHER, a citizen of the United States, residing at Houston, in the county of Harris and State 5 of Texas, have invented certain new and useful Improvements in Gins, of which the following is a specification.

This invention relates to new and useful improvements in a gin.

10 One object of the invention is to provide a device of the character described, which is specially adapted for the purpose of ginning cotton and other similar fibrous materials.

15 Another object of the invention is to provide a gin whereby the fiber will be readily stripped from the seed without injury to said fiber, provision being made for the fluffing of the fiber before it is delivered 20 from the gin to the compress.

A further feature of the invention resides in the provision of means for discharging the seed after they have been freed of the lint.

25 A still further feature of the invention resides in the provision of means for separating the motes and other small foreign bodies from the fiber.

With the above and other objects in view, 30 the invention has particular relation to certain novel features of construction, operation and arrangement of parts, an example of which is given in this specification and illustrated in the accompanying drawings, 35 wherein:

Figure 1, is a rear view of the device, showing the casing of the fluffer roller removed.

Fig. 2, is an end view.

40 Fig. 3 is an end view as viewed from the opposite end to that shown in Fig. 2.

Fig. 4, is a vertical sectional view.

Fig. 5, is an enlarged fragmentary side elevation of the ginning roller, and

45 Fig. 6, shows an end view of the stripper roller.

Referring now more particularly to the drawings wherein like numerals of reference designate similar parts in each of the 50 figures, the numerals 1, 1, refer to the end members of the casing, which are mounted upon a suitable base, and which are provided to support the operative mechanism. Mounted upon the transverse shaft 2, which

is rotatable in suitable bearings, in the upper 55 part of the casing, is the ginning roller 3. This roller is formed of a drum supported on the shaft by suitable spiders. The periphery of the drum has parallel spirally arranged grooves 4, 4, spaced a suitable distance apart, and between them there are parallel spiraled rows of plugs 5, 5, which are formed of cork or other similar material. This drum is driven through the pulley 6, fixed upon one end of the shaft 2, and 60 fixed upon the other end of said shaft, there is a large pulley 8 alined with the smaller pulley 9, which is fixed upon the end of the transverse shaft 10. Operating over these last mentioned pulleys and transmitting rotation from the former to the latter, there 70 is a belt 11. The shaft 10 is rotatably mounted in suitable bearings carried by the end members 1, 1, and within the casing and underneath the ginning roller there is a 75 cylindrical fan 12, fixed upon said shaft, said fan being formed of a cylindrical drum which is fixed upon said shaft through suitable spiders, and said drum has the radiating blades 13, spaced a suitable distance 80 apart, and extending from end to end of the drum. The fan is inclosed in front and beneath by the casing, but is exposed in the rear, and leading from the front part of the casing at its bottom, there is the discharge outlet 14, through which the lint is 85 discharged from the gin.

Mounted in the casing beneath and in the rear of the ginning roller, and in rolling contact therewith, there is the transverse 90 fluffing roller 15, which is fixed upon the transverse shaft 16. This fluffing roller is composed of a foraminated drum which is fixed on the shaft by means of suitable spiders. One end of the shaft 16 has the 95 sprocket wheel 17, fixed thereon which is driven through the sprocket chain 18, from the sprocket wheel 19, which is fixed on a sleeve 20. This sleeve is loosely mounted upon one end to the transverse shaft 21, 100 which is rotatable in suitable bearings in the end members 1, 1, and the sleeve 20 is rotated through the pulley 22, which is fixed thereon, and which, in turn, is rotated by the cross belts 23, which is driven from the 105 pulley 24, fixed on the shaft 2. The ginning and fluffing rollers are thus rotated in the direction indicated by the arrows in Fig. 4,

and the gearing is such that the fluffing roller will rotate much more rapidly than the ginning roller.

The numerals 25, 25, designate curved arms which are fixed at their lower ends to the transverse shaft 21, and whose upper ends are formed into bearings in which the shaft 26 rotates. This shaft has the stripper roller 27, fixed thereon, and the shaft is 10 rotated through a sprocket chain 28, which operates over the sprocket wheel 29, which is fixed on the sleeve 20, and the alined sprocket wheel 30 which is fixed on the corresponding end of the shaft 26. The stripper roller has a plurality of projecting beaters 31, which are preferably formed of rawhide, leather, or some similar tough material, and are pivoted at their inner ends to said roller, but are held in radiating 15 positions by centrifugal force when the machine is in operation. Fixed at its respective ends to the corresponding arms 25, and extending from end to end of the ginning roller, there is the curved shoe 32, which partially 20 surrounds the ginning roller in the rear, and whose upper edge is retracted or bent back, forming a stripper edge 33, adjacent the ginning roller.

The seed cotton is fed to the ginning roller 20 through the hopper 34, and is carried around by said roller against the stripper edge 33. The spiraled grooves 4, will engage with the lint, and carry the same underneath the shoe 32, the cork plugs 5 also engaging with the lint, by friction, and carrying the same 35 around underneath the shoe, and stripping the lint from the seed, the seed being arrested by the stripper edge 33. Meanwhile the rapid rotation of the stripper roller 27 will carry the beaters 31 against the seed and said seed will be thereby freed from the lint and forced out over the shoe and the lint will be partially fluffed thereby. The lint will then be carried by the ginning 40 roller therearound and will pass between the ginning roller and the fluffing roller, the rapid rotation of the latter of which will fluff the lint and reduce it to a soft fluffy mass which will be delivered to the cylindrical fan 12, the blades of which will carry the lint around and force it out through the outlet 14. The rapid rotation of the fan 12 will cause a discharge of the motes and other small foreign particles by centrifugal 45 force out through the opening in the casing behind said fan.

Fixed to one end of the shaft 21, there is a manual lever 35, through which said shaft may be turned, and the arms 25 and the elements carried thereby, may be adjusted 50 toward and from the ginning roller. This manual lever is provided with a rack-and-dog arrangement 36, of the well known type through which it may be locked in any 55 desired position. By this means, the strip-

ping roller 27 and the shoe 32 may be adjusted relative to the ginning roller, or may be withdrawn when it is desired to gain access to the rear part of the said roller.

What I claim is:

1. A gin for seed cotton and the like including a casing, a ginning roller mounted for rotation therein, a stripping shoe provided with an edge arranged adjacent said roller, and adapted to engage with the cotton to be ginned and to arrest the seed, but permit the passage of the lint between said shoe and the roller, and a stripper roller provided with pivotally mounted projecting beaters, mounted for rotation and operating 75 in coöperation with said shoe and provided to remove the seed from the lint.

2. A gin for seed cotton and the like, including a casing, a ginning roller rotatably mounted therein, a fluffing roller arranged adjacent said ginning roller, means for imparting rotation to said rollers in opposite directions, said means being adapted to rotate the fluffing roller at a higher rate of speed than the ginning roller, a hopper 85 through which the material to be ginned is delivered to said ginning roller, a shoe provided with a stripping edge adjacent the ginning roller, and arranged between the hopper and the fluffing roller, said shoe ar- 90 resting the seed, but permitting the passage of the lint between it and the ginning roller to the fluffing roller, and a stripping roller provided with radiating pivotally mounted beaters arranged to coöperate with said 100 edge, whereby the seed are extracted from the fiber.

3. A gin for seed cotton and the like, including a casing, a ginning roller rotatably mounted therein, a fluffing roller arranged 105 adjacent said ginning roller, means for imparting rotation to said rollers in opposite directions, said means being adapted to rotate the fluffing roller at a higher rate of speed than the ginning roller, a hopper through which the material to be ginned is delivered to said ginning roller, a shoe, provided with a stripping edge adjacent the ginning roller, and arranged between the hopper and the fluffing roller, said shoe ar- 110 resting the seed, but permitting the passage of the lint between it and the ginning roller to the fluffing roller, a stripper roller, radiating beaters pivotally mounted on said stripper roller and arranged to coöperate 115 with said edge, whereby the seed are extracted from the fiber, and means for adjusting said shoe and stripper roller toward and from the ginning roller.

4. A gin for seed cotton, and the like including a casing, a gin roller rotatably mounted therein, whose periphery is provided with rows of friction plugs, a fluffing roller arranged adjacent said ginning roller, means for imparting rotation to said rollers 125

in opposite directions, said means being adapted to rotate the fluffing roller at a higher rate of speed than the ginning roller, a hopper through which the material to be ginned is delivered to the ginning roller, a shoe provided with a stripping edge adjacent the ginning roller and arranged between the hopper and the fluffing roller, said shoe coöperating with the friction plugs of said ginning roller, and arresting the seed, but permitting the passage of the lint between it and said roller to the fluffing roller, and a stripping roller provided with radiating beaters arranged to coöperate with said edge whereby the seed are extracted from the fiber.

5. A gin for seed cotton and the like including a casing, a ginning roller rotatably mounted therein, whose periphery is provided with spiraled grooves spaced apart and spiraled rows of friction plugs between said grooves, forming a friction surface for said roller, a fluffing roller arranged adjacent said ginning roller, means for impart-

ing rotation to said rollers, in opposite directions, a hopper through which the material to be ginned is delivered to said ginning roller, a shoe provided with a stripping edge, adjacent the ginning roller and arranged between the hopper and the fluffing roller, said shoe coöperating with said friction surface to arrest the seed, but permitting the passage of the lint between it and the ginning roller of a stripping roller, radiating beaters pivotally mounted on said stripping roller and arranged to coöperate with said edge whereby the seed are extracted from the fiber and means for adjusting said shoe and stripping roller toward and from the ginning roller.

10 In testimony whereof I have signed my name to this specification in the presence of two subscribing witnesses.

EDWARD R. TISCHER.
